LIQUID DISPENSER

Patrick M. Prosser, Jacksonville, Fla.

Application June 26, 1935, Serial No. 28,539

10 Claims. (Cl. 225—21)

This invention relates generally to liquid dispensers, and more particularly to a dispenser for association with a motor vehicle, boat or other vehicle.

5 The primary object of the invention is to provide means of simple and compact nature in connection with a vehicle, by means of which the occupants may readily obtain fluid therefrom without the necessity of stopping for such refreshment.

10 A further object of the invention is to provide a liquid dispenser of such nature that it may be quickly and easily applied to the vehicle within convenient reach of the occupants thereof, and which may be as readily detached when required for cleaning or replenishing.

15 A further object of the invention is to provide means associated with a liquid dispenser of the character mentioned whereby the liquid may be readily withdrawn therefrom, and which also has associated therewith means to prevent dripping or waste of the fluid.

20 A still further object is to provide a liquid dispenser capable of being furnished with the vehicle as standard equipment, or which may be constructed in the form of an attachment and easily adapted to vehicles of various forms and types.

25 With these objects in view, together with others which will appear as the description proceeds, the invention consists in the novel construction, combination and arrangement of parts all as will be described more fully hereinafter, illustrated in the drawing, and particularly pointed out in the claims.

30 In the drawing:

35 Figure 1 is a longitudinal sectional view taken through a liquid dispenser constructed in accordance with the invention and showing the same attached to a conventional form of motor vehicle.

40 Figure 2 is a sectional view taken upon line 2—2 of Figure 1.

45 Figure 3 is an enlarged detailed perspective view of the drip catcher associated with the receptacle.

50 Figure 4 is a detailed perspective view of the supporting plate employed in connecting the tank with the vehicle, and

55 Figure 5 is a transverse sectional view through a liquid dispenser of slightly modified form.

Referring now more particularly to the drawing, the liquid dispenser comprises a receptacle including an inner container or tank 6 and an outer shell or casing 7; the walls of said con-

tainer and casing being spaced apart to provide an insulating space between them. This space may be filled with packing or suitable insulation 8 or, if desired, the space between the walls may be a vacuum or dead air space. One 5 end of this tank is closed by a cap 9 capable of being readily applied to or removed from the opening, and a gasket 10 interposed between the cap and the mouth of the tank serves to hermetically seal the same when the cap is properly 10 applied. In the present instance this cap is of the screw variety, but it will be understood that any other type of cap may be employed.

Rigidly secured to one side of the casing or shell 7, and preferably near the filling opening of 15 the tank is a plate 11. This plate may be riveted, spot-welded or in any other approved manner attached to the shell. The plate is undercut or beveled at its longitudinal edges as at 12 to fit within the dove-tail recess formed in the underside of a clamp plate 13 to be secured to the vehicle. The clamp plate has threaded in one edge thereof a set screw 14, the inner end of which engages within the notch or recess 15 in the edge of plate 11 when the latter has moved a predetermined and proper distance within the clamp plate. Any desired means may be employed for securing the clamp plate 13 to the vehicle, the means here shown comprising an anvil 16 projecting upwardly from the plate at one end thereof and to 20 engage with the outer face of the instrument board or panel 17 of a motor vehicle. A screw clamp 18 is threadedly supported in an upstanding bracket 19 carried by the clamp plate 13, in order that the panel 17 may be rigidly clamped 25 between the anvil and the screw. To insure rigidity of this support a pair of anvils and associated screw clamps are employed as shown in Figure 2.

Secured to the outer face of the cap 9 is a 40 face plate 20, preferably of ornamental design and capable of being finished in accordance with the finish of the vehicle. A discharge faucet or valve 21 of conventional form is carried by the face plate and cap and is so disposed as to be at 45 the lower side of the receptacle when the screw cap is properly applied to the neck of the receptacle.

The lower portion of the face plate 20 carries a drip catcher which includes a drain pipe 22 arranged in parallel relation with the body of the valve 21 and immediately beneath the same. This pipe is provided at its forward end with a basin 50 23 to snugly engage with the discharge nozzle 24 of the valve. Depending from the forward end 55

of the drain pipe is a bracket 25, which includes a rearwardly disposed rod 26 arranged parallel with the drain pipe and extending loosely through an opening in face plate 20. The rod 26 carries 5 an expansion spring 27 engaged at one end with an arm carried by the rear face of plate 20, and abutting at its opposite end with a disc 29 secured to the rod. The drain pipe 22 also slides through a suitable opening in face plate 20 and has detachably secured at its rear end a drain hose 30. The construction is such that the spring 27 normally holds the drain pipe 22 with its basin 23 snugly engaging the discharge end on nozzle 24 of the valve, and any drip therefrom will pass into 10 the pipe and out through the flexible hose 30. However, pressure applied to the bracket 25 causes the drip catcher to move against the tension of spring 27, uncovering the nozzle 24.

The embodiment here described is adapted particularly for use in connection with motor vehicles and is associated with the instrument board thereof. When properly applied, the tank is maintained rigidly in horizontal position with the valve so located as to be capable of draining substantially all the contents from the receptacle. When it is desired to obtain fluid from the tank, it is but necessary to apply a glass or cup to the bracket 25 and force the same rearwardly against the tension of spring 27 until the edge of the cup passes beyond the discharge nozzle 24. By 20 then operating the valve, the glass or cup may be filled and upon withdrawal of the same from beneath the nozzle the drip catcher automatically moves to such position as will cause any drip or afterflow from the valve to pass out through the drain hose. The screw and notch 14-15 are so related that when in cooperative locking engagement the face plate 20 is substantially aligned with the instrument board or panel 17 so as not to 25 project any part of the device any appreciable distance beyond the said instrument panel. When it is desired to refill the receptacle, it is but necessary to loosen the set screw 14, disconnect the drain hose 30 from drain pipe 22 and slide the container forwardly. The screw cap 9 may then be removed and the supply of fluid replenished, whereupon the tank may be attached and securely held in the manner heretofore described.

The tank will be of such size as to contain an ample supply of water, coffee or other fluid. By reason of the spaced walls 6-7, the fluid will more or less retain its original temperature until consumed.

It may be found desirable to include in the structure means whereby different fluids may be included in a single structure, for instance, where it may be found desirable to carry hot coffee as well as ice water. In Figure 5 of the drawing there is illustrated a modification providing for such necessity, wherein the shell 7 has arranged therein a pair of tanks 31-32, spaced from one another and surrounded with suitable packing material 8. By thus insulating the tanks from each other, the fluids contained therein will retain their original temperatures. It will be understood, of course, that the means for attaching the device in Figure 5 to the instrument panel will be substantially the same as that shown in the preferred construction heretofore described, and it will also be understood that each tank 31 and 32 will be equipped with a discharge faucet and drip catcher as heretofore described.

From the foregoing, it is apparent that I have disclosed means of extremely simple construction 75 for the accommodation of liquids conveniently

within a vehicle, and one wherein the various objects heretofore set forth may be effectively attained. It will be understood, however, that variations in the details of construction and arrangement of parts may be resorted to without departing from the spirit of the invention as defined by the claims.

I claim:

1. In a liquid dispensing apparatus, a fixed clamp plate, a receptacle, a slide member carried by one side of said receptacle and engageable with said clamp plate, means for locking said slide and clamp plate against relative movement, a drain valve for said receptacle arranged upon the latter opposite to said slide member.

2. In a liquid dispensing apparatus, a fixed clamp plate, a receptacle, a slide member carried by the receptacle and engageable with said clamp plate, means for securing said slide against movement in said clamp plate, a drain valve for said receptacle, and a drip catcher associated with said valve and carried by said receptacle, said valve and drain arranged on said receptacle in a position opposite to said member.

3. In a liquid dispensing apparatus, a receptacle having an open end, a cap to close said end, a plate carried by said cap, a valve carried by the cap and extending through said plate, a discharge nozzle for said valve, a drain pipe slidable through said plate, a basin on said pipe adapted to engage with the discharge nozzle of said valve, and means for yieldably holding said pipe with its basin associated with said nozzle.

4. In a liquid dispensing apparatus, a receptacle, a cap closing one end of said receptacle, a valve carried by and extending through said cap, a discharge nozzle for said valve, a member depending from said cap, a drain pipe slidable through said member, a basin on said pipe to engage the said nozzle, a rod carried by said pipe disposed parallel therewith and extending through said member, and a spring associated with said rod and normally maintaining said pipe with its basin engaged with said nozzle.

5. In combination, a bracket adapted to be attached to a fixed part of a vehicle, a receptacle, means on one side of the receptacle whereby the same may be attached to said bracket and be sustained in substantially horizontal position, and a drain valve for said receptacle at the lower side 50 of the receptacle, thus affording complete drainage for the receptacle.

6. The combination with a vehicle having a fixed part presenting a plane surface, of a receptacle, means for supporting said receptacle 55 behind said surface with its open end substantially in the plane of said surface, a closure for said end, and a valve for said receptacle.

7. The combination with a vehicle having a fixed part presenting a plane surface, of a receptacle, means on a side of the receptacle for supporting the latter in substantially horizontal position, and a drain valve for the receptacle arranged to lie at the lower side of the latter when the receptacle is thus suspended.

8. The combination with a vehicle having a fixed part presenting a plane surface, of a receptacle, means on a side of the receptacle for attachment to said fixed part to suspend the receptacle in substantially horizontal position, and a drain valve for the receptacle arranged to lie at the lower side of the receptacle when the latter is thus suspended.

9. The combination with a vehicle having a

fixed part presenting a plane surface, of a receptacle open at one end, means for supporting said receptacle behind said surface with its open end substantially in the plane of said surface, a closure for said end, and a discharge valve carried by said closure.

5 10. The combination with a vehicle having a

fixed part presenting a plane surface, of a receptacle open at one end, means for supporting said receptacle behind said surface with its open end substantially in the plane of said surface, a closure for said end, and a discharge valve and 5 catch basin carried by said closure.

PATRICK M. PROSSER.
